ROBERT W. BURROWS, OF PETALUMA, CALIFORNIA, ASSIGNOR OF ONE-HALF TO HOBBS WALL & CO., OF SAN FRANCISCO, CALIFORNIA, A CORPORATION OF CALIFORNIA.

VENEER SLICING AND SCORING MACHINE.

1,327,983.

Specification of Letters Patent. Patented Jan. 13, 1920.

Application filed December 3, 1918. Serial No. 265,085.

To all whom it may concern:

Be it known that I, ROBERT W. BURROWS, a citizen of the United States, residing at Petaluma, in the county of Sonoma and 5 State of California, have invented new and useful Improvements in Veneer Slicing and Scoring Machines, of which the following is a specification.

This invention relates to a veneer slicing 10 and scoring machine.

In the manufacture of veneer, such as is employed in the making of fruit baskets and the like, it has been common practice to slice or cut the veneer in one machine and 15 then to score or partly cut the veneer along the folding lines in a second machine to permit the veneer to be properly folded when the baskets are being formed. This method is more or less costly and wasteful, 20 first, because it requires two separate machines and operations, and, secondly, repeated handling of the material, thereby causing a decided loss in the cost of manufacture due to the additional labor required and the resultant increase in material 25 damaged.

The object of the present invention is to provide a simple, substantial, easily operated machine for slicing veneer, such as is 30 employed in the manufacture of fruit baskets and the like, which will not only slice the veneer but will also score the same, thereby producing a finished product in one operation, that is, a slice of veneer which 35 has simultaneously been scored along the folding lines. Further objects will herein-after appear.

The invention consists of the parts and the construction, combination and arrangement of parts which will be hereinafter described and claimed, having reference to the accompanying drawings, in which—

Figure 1 is a side elevation of the machine.

Fig. 2 is a perspective view of a slice of veneer which has also been scored.

Fig. 3 is a section on the line 3—3 of Fig. 1.

Fig. 4 is a plan view of Fig. 1.

Referring to the drawings in detail, A indicates the base of the machine, which, in this instance, supports a pair of guide rails 2 and 3. One of the rails is supported di-

rectly on the frame A, while the opposite rail 3 is supported by a pair of arms 4 formed as an integral part of the main frame A. The rails 2 and 3 are positioned on an angle of 45° and are provided for the purpose of supporting and guiding a rectangular shaped frame 5 to which reciprocal movement is imparted by means of a link 6 and a crank 7, the crank 7 being secured on a shaft 8 supported in a journal 9 and driven by means of a pulley 10.

The frame 5 is provided for the purpose of supporting a slicing knife 10 and a pair of scoring knives 11. The slicing blade is secured by means of screws 12 to a cross bar 13 rigidly secured on the frame 5 to permit the blade to be readily removed for resharpening, repairs or otherwise. The scoring knives 11 are supported in arms 14 formed as integral parts of sliding blocks 15. These blocks are supported between guide rails 16, both of which are rigidly secured on a plate 17 carried by the frame 5. Also formed as an integral part of the sliding blocks 15 is a pair of guiding arms 18. These arms straddle cam members 19 which are carried by a bracket plate 20 secured, as at 21, to the main frame A. Reciprocal movement imparted to the frame 5 will therefore cause the knife 10 to move in such a manner that it will produce a drawing cut across the block 22, from which the veneer is sliced, and it will simultaneously impart a reciprocal movement to the sliding blocks 15 which will cause the scoring knives 11 to pass across the face of the veneer along converging lines, such as shown at 23 (see Fig. 2), as will hereinafter be described.

The block from which the veneer is to be cut has a cross sectional formation, as shown in Fig. 2. This block is supported on a feed table 24 in front of a slidable back-stop. Said table is formed as an integral part of the main frame A, movement being imparted to the back-stop by means of a pair of rack bars 26, pinions 27 secured on a shaft 28 and a hand crank 29.

In actual operation, referring to Figs. 1 and 3, it will be seen that it is only necessary to place the block 22 upon the feed table 24. A back-stop 30 on the table forces the block forwardly against the plate 17 carried by the sliding frame. This plate

therefore not only serves as a support for the scoring knives, but also as a stop plate for the block from which the veneer is sliced. The reciprocal movement imparted 5 to the frame 5 therefore causes the knife to travel across the face of the block 22 in such a manner that a drawing cut is produced. This is due to the fact that the frame 5 travels on an angle of 45°, while 10 the knife 10, together with the block 22, is standing in a horizontal position. The downward movement of the frame 5 furthermore pulls the scoring knives 11 across the face of the block, and, as said knives are 15 carried by the sliding blocks 15 and these are in turn moved toward each other, due to the fact that the arms 18 embrace the cam members 19, it can readily be seen that the face of the block is first of all scored 20 on the converging lines shown at 23 (see Fig. 2), and, secondly, that the slicing knife 10 will cut the veneer.

The movement of the knife 10 is limited so that when the lowest position is reached 25 the block 22 or veneer slice will just be cut. The cutting edge of the knife 10 will therefore just reach the surface of the table 24 and will therefore not have a tendency to break the lower edge of the block 22 and 30 produce a ragged edge. A wooden filler plate may be placed on the table to permit the first stroke of the knife to partly enter the same, thus further insuring a clean cut or slice after each reciprocation of the knife 35 and frame 5.

While a crank arm 29 is provided for the purpose of operating the feed table I wish it understood that any other feeding mechanism may be employed; similarly, that the 40 materials and finish of the several parts forming the machine may be such as the experience and judgment of the manufacturer may dictate.

Having thus described my invention, what 45 I claim and desire to secure by Letters Patent is:

1. In a machine of the type set forth, a slicing knife, means to operate the knife, scoring means, and means to actuate the 50 scoring means simultaneously with the knife so as to cause same to move diagonally in the plane in which the knife moves and to score a face of the material during slicing of the latter.

2. In a machine of the type set forth, a slicing knife, means to operate the knife, a pair of scoring means, and means to actuate the scoring means simultaneously with the knife so as to cause same to have a relative divergent movement diagonally in the 60 plane in which the knife moves and to score a face of the material during slicing of the latter.

3. In a machine for slicing and scoring 65 veneer, a slicing knife, means to operate

the knife, a scoring knife, and means to actuate the scoring knife simultaneously with the slicing knife so as to cause same to move across the face of the material diagonally in the plane in which the knife moves and 70 to score a face of the material during slicing of the latter.

4. In a machine of the type set forth, slicing means, means to operate the slicing means in one direction, scoring means, means 75 to mount the scoring means whereby same will partake of said movements of the slicing means and may move independently of the slicing means in a direction different from that in which the slicing means operates, and means to control said independent movement of the scoring means and to score a face of the material during slicing of the latter.

5. A combination veneer slicing and scoring machine comprising a frame disposed on an angle, a table horizontally disposed with relation thereto, a sliding frame mounted in a guiding frame, a horizontally positioned slicing knife carried by said sliding frame, a pair of scoring knives also carried by the sliding frame, means for imparting a reciprocal movement to the sliding frame and means for simultaneously imparting a lateral movement to the scoring knives and 95 to score a face of the material during slicing of the latter.

6. A combination veneer slicing and scoring machine comprising a frame disposed on an angle, a table horizontally disposed 100 with relation thereto, a sliding frame mounted in a guiding frame, a horizontally positioned slicing knife carried by said sliding frame, a pair of scoring knives also carried by the sliding frame, means for imparting 105 a reciprocal movement to the sliding frame, means for simultaneously imparting a lateral movement to the scoring knives, said means comprising a sliding block supporting each scoring knife, guide rails supporting said sliding blocks and a pair of cam members adapted to impart a lateral movement to the sliding blocks and the scoring knives carried thereby during the reciprocal movement of the sliding frame and to score 115 a face of the material during slicing of the latter.

7. In a machine of the type set forth, a reciprocal slicing knife, scoring means movable laterally of the plane in which the knife 120 moves, and means whereby to effect simultaneous movement of the knife and scoring means and synchronously therewith lateral movement of the scoring means independent of the knife movement and to score a face 125 of the material during slicing of the latter.

8. In a machine of the type set forth, a reciprocal frame, a slicing knife carried thereby, a slid able scoring knife carried by the frame so as to partake of the reciprocal 130

movements thereof, and to move laterally of the plane in which the frame reciprocates, and means for actuating the scoring knife to move same laterally by and during reciprocal movement of the frame and slicing knife and to score a face of the material during slicing of the latter.

In testimony whereof I have hereunto set my hand in the presence of two subscribing witnesses.

ROBERT W. BURROWS.
